UNITED STATES PATENT OFFICE.

JAMES ALBERT LOCKE, OF KALISPELL, MONTANA.

KNOCKDOWN PLAYHOUSE STRUCTURE.

Application filed May 8, 1922. Serial No. 559,258.

To all whom it may concern:

Be it known that I, JAMES A. LOCKE, a citizen of the United States, and a resident of Kalispell, in the county of Flathead 5 and State of Montana, have invented certain new and useful Improvements in Knock-down Playhouse Structures, of which the following is a specification.

This invention relates to a knock-down 10 playhouse structure.

The object of the invention is to produce a novel building structure of the above character which will give the appearance of a log cabin.

15 It is a further object of the invention that the structure be adapted to serve as a playhouse for children and that it be highly artistic in appearance.

It is also an object of the invention that 20 the building structure be composed of minimum number of parts and easily assembled to form a log cabin.

It is a still further object of the invention that the structure be adapted to permit the 25 inclusion of a porch and a roof therefor if so desired.

Other objects, and objects relating to details of construction, combination and arrangement of parts will hereinafter appear 30 in the detailed description to follow.

The invention is illustrated by way of example in the accompanying drawings, in which:—

Figure 1 is a view in side elevation of an 35 assembled log cabin or playhouse embodying the present invention.

Figure 2 is an end elevation of the same.

Figure 3 is a group view illustrating the 40 structural elements utilized in providing a window or door in one of the walls of the playhouse structure.

Figure 4 is a detailed view illustrating the manner in which the miniature logs forming the walls of the structure are locked 45 together.

Figure 5 is a group view illustrating the elements forming the roof of the structure.

Figure 6 is a group view illustrating the 50 structural parts and manner of connecting the same for forming the porch of the log cabin or playhouse.

Figure 7 is a detailed view of the removable floor used for the interior of the playhouse or log cabin.

55 Figure 8 is a view similar to Figure 1 of a slightly modified form of playhouse.

Figure 9 is a detailed view of one of the side frame members employed in the structure shown in Figure 8 for forming the enlarged door.

Figures 10 and 11 are detailed perspective views of the sill logs used for the enlarged door shown in Figure 8.

Referring to the drawings more particularly, the knock-down playhouse structure 65 consists in the side walls W made of miniature logs, the end walls W' likewise made of miniature logs, the extension or porch P, the roof R for the interior of the playhouse and the extended portion R' for the porch P, and 70 the chimney C.

The side walls W are each formed of a plurality of miniature logs 10, said logs 10 being of the length shown and each having an upper and lower flat edge as illustrated 75 in Figure 4, an inner flat surface as also illustrated in Figure 4, and an outer surface 11, unfinished and preferably left with the bark thereon. Each end wall W' also consists in a plurality of superposed miniature 80 logs 12 which likewise have an upper and lower flat surface and an inner flat surface the same as the side logs 12. Also the exterior surface 13 of the end logs is unfinished and preferably the bark left thereon 85 the same as the side logs 10. The ends of each side log and also of each end log are formed, in each instance, with a pair of notches 14 preferably of the shape and depth shown, and the outer surface of the 90 notched ends of the logs are in each instance provided with an insertion 15, said insertion being adapted to extend upon each side of the notches 14 as best illustrated in Figure 3. The notches 14 are adapted to 95 permit the inter-locking of the end logs with the side logs in a manner which is thought to be apparent.

The lowermost side logs 15 extend from one end of the house structure, said extension in each instance being indicated by the reference numeral 16 and these extended portions of the logs being adapted to serve as a supporting means for the porch P. The porch P otherwise consists in a floor F 100 which comprises a board corresponding in width and length to the porch P and having its sides formed with an offset 17 occurring upon the lower face thereof and along the opposite edges of the board whereby to permit said board to be fitted upon the log extensions 16. Also each board is provided 105 110

with an opening or hole 18 at each corner thereof adapted to receive the lower reduced end portion 19 of posts 20. The posts 20 are four in number, corresponding to the 5 number of holes 18, and the posts on the same side of the porch are in each instance connected by a rail R, said rail being preferably circular in cross section and having each of its ends provided with a pin extension 21 adapted to extend into a suitable opening 22 in the associated post 20. Also between each rail and floor there may be extended a plurality of uprights 23, each upright having formed at each of its ends a 15 pin extension 24 adapted to be extended into openings in the associated rail R and floor F. As is obvious from the porch construction described, the same is easily knocked down or disassembled and likewise easily re- 20 assembled.

In assembling the playhouse structure the lowermost logs 15 are first positioned and then the end logs positioned for tying these two side logs together.

25 The floor F' for the interior of the cabin or playhouse specifically shown in Figure 7 consists in a board having its one end provided with two notches 27; which end should be disposed adjacent the porch P. 30 Each lower longitudinal edge of the floor board is provided with an offset similar to the offset 17 provided in the similar edges of the porch floor F. The floor board F' is adapted to be positioned so that the lower, 35 most side logs will support the same, the same as the porch floor F. It is also preferable that the end wall W' facing the porch P be provided with a door, as shown in Figure 2. For providing this door I provide the two side frame members 28 and the upper and lower sills 29. Each side frame member 28 is specifically illustrated in Figure 3 and consists in a channel member as shown, the bridge terminating at each 45 end in a lug or extension 30. The frame members are positioned so that the channel 31 is disposed on the outer side thereof. The sills 29 are also specifically shown in Figure 3 and likewise consist in a channel member, the bridge portion of which is provided adjacent each end with an opening 32 adapted to receive a lug or extension 30 of the side members 28. Also the sills 29 are positioned so that their channels 33 will 50 be disposed exteriorly. The side members 28 and sills 29 when joined form a door frame as illustrated in Figure 2 of the drawings which is adapted to accommodate a door D. The door D is preferably of solid 55 structure and may be hinged to one of the side frame members 28 if desired. Also the door is provided with a suitable slide bar 34 which is adapted to be projected into a suitable opening in the adjacent side frame member 28 for locking the door in its closed

position. The lowermost end log 12 associated with the the door D has its edge contiguous with the lower sill 29 reduced as indicated at 34, Figure 3, so that the same may project into the channel 33 of said 70 sill. Also the end log occurring first above the upper door sill 29 has its lower edge reduced in a similar manner so that the same may project into the channel 33 of the upper sill 29. 75

For closing the space between side frame members 28 of the door and the side walls W there are provided in each instance a plurality of short logs 35, each short log having its one end formed in the usual manner, that is, with notches 14 and insertion 15 as previously described, while its other end is pointed as shown in Figure 3 at 36 and this pointed end is adapted to be projected into the channel 31 of the door frame members 28. As is obvious by this arrangement the inner ends of the shorter logs 35 are rigidly held in position. 80

Also one or more windows may be provided for the side walls or the end walls if desired. Such a window is shown in Figure 1 and consists in the upper and lower sills 37 and the two side frame members 38. The upper and lower sills 37 correspond in structure to the sills 29 of the door D, and the side frame members 38 correspond to the side frame members 28 of the door D. In this instance logs are also used for filling the space between the side frame members 38 and end walls of the structure as indicated at 39. 95

In forming the gable at each end of the structure, the end logs are gradually shortened as they proceed upwardly, as illustrated in Figure 2. One of these end logs is specifically shown in Figure 5 and as is seen the same has its ends inclined in opposite directions as at 40. The log shown in Figure 5 represents the uppermost log of the gable structure and is indicated by reference numeral 42. This log is provided upon its bottom edge with a pair of notches 43 and upon its upper edge with a notch 44. Also the log occurring directly beneath the log 42 and indicated by the reference character 45 has its upper edge provided with a pair of notches in register with the notches 43 of the log 42 and likewise its lower edge provided with a pair of notches in register with notches provided in the log therebelow. These notches are adapted for receiving the ends of longitudinals 46. The particular construction of the longitudinals 46 is shown in Figure 5, and as seen each end thereof is provided with a pair of notches 47 which are adapted to inter-lock with the end logs forming the gable of the structure. 110

I also provide a ridge pole of the character shown in Figure 5 and indicated by the 120

reference numeral 47, which is triangular in shape and the base portion thereof being formed with a protrusion 48 which extends the entire length of the ridge pole and is 5 adapted to seat in the notches 44 of the gable logs 42. The roof R consists in a plurality of boards 49. Each board as shown in Figure 5 has its upper end beveled as at 50 adapted to fit against the one side of the 10 ridge pole 47. Also each board adjacent its lower end has its bottom face formed with a transverse groove 51 which is adapted to receive the upper edge of the uppermost side log 10 thus to hold the board in position. 15 The ridge pole 47 may be extended at one end to project over the porch P, and likewise the uppermost side logs may be extended and thus by means of boards 49 form the roof R' for the porch P. The chimney C 20 preferably consists in a hollow box portion 52 which has two of its opposing sides formed with an angular recess adapted to permit the seating of said box upon the apex of the roof R. The upper portion of the 25 chimney may consist in a plurality of blocks 53 which are of different dimensions and placed one upon the other to give the appearance of a chimney.

The structure shown in Figures 8 to 10 30 inclusive corresponds substantially to the structure heretofore described with the exception that one side wall W is provided with an enlarged opening D. Reference numerals employed in the description of Figures 1 to 7 refer to similar elements and parts of construction shown in Figures 8 to 35 11 inclusive. In fact the larger portion of parts employed for building or assembling the structure shown in Figure 8 may be employed for assembling the structure shown in 40 Figure 1. In this instance the side wall W has the lowermost log 15 additionally formed with a pair of tenons 54. A pair of 45 side frame members 55 are provided, each being channel shaped, as shown in Figure 9, and having their side portions 56 projecting at each end, as shown, to form the protrusions 57 adapted to receive therebetween the tenon 54. The uppermost side log shown in 50 Figure 10 has its lower edge provided with a pair of similar tenons 55' which may be received by the projections or protrusions 57 of the side frame members 55. The channel 55 of each side member 55 is disposed 55 outwardly with relation to the opening D, and the space between these side frame members and the end walls of the structure is closed in each instance by short logs 59, said logs being fitted and secured in position in the manner the logs 35 are positioned and secured previously described.

It is believed from the foregoing descrip-

tion that it is apparent how the present play house structure may be knocked down or assembled in a quick manner and that after 65 the same has been properly assembled it will serve as a playhouse for children. Preferably as heretofore stated the lowermost side logs 15 are first positioned then the same logs of the end walls and then the floor F'. 70 After this the side walls and end walls are built and the windows and doors desired inserted, and then the roof R is positioned, or assembled together with the roof extension R' for the porch P. The porch P may be 75 assembled at any period after the lowermost logs 15 have been laid.

It may be also here stated that the structure as a whole may be knocked down and stored in a comparatively small space and 80 furthermore that the structure may be erected at any place desired without providing any foundation therefor.

While I have shown and described the preferred form of my invention, I wish it to 85 be understood that I am aware of the fact that the construction, combination and arrangement of parts may be changed by those skilled in the art without departing from the spirit of the invention as indicated by the 90 appended claims.

I claim:

1. A knock-down playhouse structure of the character described comprising miniature logs for forming the walls thereof, said logs 95 being notched to mechanically tie the same together and the lowermost logs of the side walls being extended at one end thereof, a one piece floor adapted to rest upon the extended portions of the side logs and form a 100 porch, a door in the wall adjacent the porch, a separable roof for the structure, said roof extending over the porch, and a one piece chimney adapted to be positioned upon said 105 roof.

2. A toy house construction of the character described comprising a plurality of logs adapted to be assembled into a house and similar ends of the lowermost logs being extended to provide a support for a porch 110 floor, and extensions of the uppermost side logs of the structure and the ridge pole whereby to provide a supporting frame for a roof to cover said porch floor.

3. In a toy house construction of the character described, a plurality of logs whereby a house structure may be formed, and a one-piece floor adapted to be seated within said house structure, said floor and adjacent logs having co-operative notches, and projections 115 whereby the floor may be supported and also utilized for bracing said housing structure.

JAMES ALBERT LOCKE.
